UNITED STATES PATENT OFFICE.

LOUIS E. BAUER, OF SPRINGFIELD, OHIO, ASSIGNOR TO THE BAUER BROTHERS COMPANY, OF SPRINGFIELD, OHIO, A CORPORATION OF OHIO.

ATTRITION MILL.

Application filed December 27, 1921. Serial No. 326,332.

To all whom it may concern:

Be it known that I, Louis E. BAUER, a citizen of the United States, residing at Springfield, in the county of Clark and State of Ohio, have invented certain new and useful Improvements in Attrition Mills, of which the following is a specification.

My invention relates to improvements in attrition mills of the kind which employ vertically arranged grinding disks driven from longitudinally-arranged drive shafts.

Mills of this kind are constructed of two types—single disk, in which but one of the disks revolve, and double disk, in which both disks revolve, but in opposite directions. With the single disk type, but one drive shaft is employed, while with the double disk type two independent drive shafts are used, arranged on opposite sides

20 of the grinding casing, and it has been customary in both types to mount all of the operating parts upon a single base structure. In the single disk type of mill, however, the drive shafts, grinding heads and disks, and 25 other operating parts, such as the quick releasing mechanism, is an exact duplicate of one-half of the double disk type, but due to the construction of the bases for the respective types, as well as the enclosing casings for the grinding heads, it has not been 30 possible to convert one type into the other by utilizing those parts which are common to both, nor has it been possible to carry in stock certain parts such as the base structure, which could be used in the assembly of either type.

An object of this invention is to devise a base unit which may be used for either type of mill—one of the base units being 40 employed for the single disk type and two of the base units for the double disk type, which units in the latter type will be placed end to end so as to form in effect a divided base; a further object being also to devise 45 casing parts for the grinding members so fitted and supported from the base structure that when it is desired to convert the machine from one type to another, the casing parts may be readily removed and be replaced by other casing parts suitable to the converted type of mill.

A further object of the invention is to devise a simple and economical construction of mill from a manufacturing standpoint 55 which will reduce the number of structural

parts necessary to be carried in stock and thereby better systematize the shop practice in the manufacture thereof; a more specific object in this connection being to devise a base unit suitable for both types of mills and which in the double disk type is interchangeable in the sense that it may be used either as the left hand or right hand half of the divided base structure.

In the accompanying drawings: 55

Fig. 1 is a side elevation partly in section of double disk construction.

Fig. 2 is a longitudinal section of a portion of the same.

Fig. 3 is an end view of one of the bases. 70

Fig. 4 is a section on the line 4—4 of Fig. 1 with packing gland removed.

Fig. 5 is also a section on the line 5—5 of Fig. 7.

Fig. 6 is an end view of the single disk 75 machine.

Fig. 7 is vertical sectional view of the casing for the grinding heads and feed spout of the single disk construction.

Fig. 8 is a section on the line 8—8 of 80 Fig. 6.

In constructing the machine as a double disk mill as shown in Figs. 1, 2, 3 and 4 two base members 1 and 2 are employed constructed in all respects duplicates of each other. Each base member has integrally formed pedestals 3, which support the integral housings 5 for the bearings of the drive shafts 6.

These housings also carry supporting 90 spiders 7 for supporting the stators of electric motors, the rotors of which are mounted on the shafts 6, the details of this arrangement being more fully described in an application of Allan P. Daniel, filed Jan. 31, 1922, Ser. No. 523,101.

Connected with the shafts 6 are grinding heads 8 of the usual form which operate in a casing constructed and supported in the manner later to be described. The inner 100 adjacent ends of the bases 1 and 2 are each formed with an integral vertically-extending wall 9, the ends of which are projected inwardly, as indicated at 9^a, (Fig. 1) and formed on their vertical edges with 105 enlarged flat finished faces 9^b; these faces forming abutting surfaces between the respective base members when assembled. Each of these walls has upwardly-projecting ears 10 the inner faces of which are in 110

line with, or formed as continuations of the faces 9^b, and rods or studs 11 threaded at each end to receive nuts 11^a, serve to connect adjacent ears together in assembling the bases; additional fastening devices in the nature of a pair of rods 12, threaded at each end to receive nuts 13, serving to connect the lower portions of the walls.

Threaded on each end of the respective rods 11 is a cap-screw 14 upon which are pivotally mounted the ears 15 of a pair of covers 16 which form the upper portion of the grinding head casing; the covers being connected together at their adjacent edges 16 by a bolt 17 passing through the ears 18 and also being connected to the walls 9 by bolts 17^a passing through ears 18^a projecting respectively from the covers and walls.

Each of the walls 9 has on its upper edge 20 a central recess 9^c and each of the covers 16 has a corresponding recess 16^a; the respective recesses co-acting together to form circular openings whose centers are the axes of the shaft 6. The opening on one side of the 25 machine is closed by a circular plate 19, secured to the wall and cover members by bolts 20, apertured to receive the shaft 6 and divided vertically to permit its removal without disturbing the shaft; a gland 19^a 30 being secured to the edges of the aperture about the shaft. The opening on the opposite side of the machine is closed by a feed spout 21, which may be of any suitable construction, an example of which is shown and 35 described in another application of the said Allan P. Daniel, Ser. No. 549,479 filed April 4, 1922.

In building a single disk mill, as shown in Figs. 5, 6, 7 and 8 a semi-circular plate 22 40 is secured by bolts 23 to the edge of the recessed portion of the wall of the base member 2. A casing member 24 has lugs 25 which are secured to lugs 26 on the wall 9 and lugs 27 on the plate 22 by bolts 28. 45 The casing member also has ears 29 which are secured to the ears 10 previously referred to by bolt 30.

The outer side of this casing member is 50 closed by a laterally swingable casing member 31 having formed as an integral part thereof a feed spout 32. This casing member 31 is hinged at both sides so as to be opened in either direction. It has a pair 55 of bosses 33, on each side thereof, in each of which is threaded a hinge stud 34, the lower plain end of which is journaled in a boss 35. The upper bosses 35 are cast integrally with 60 the casing member 31, while the lower bosses 35 are formed on brackets 36, which are secured to the base 2 by the rods 37 threaded at each end to receive nuts 38, and also by cap-screws 39 which screw into openings 40 in 65 the base.

The casing member 31 is secured rigidly 70 in position by bolts 41 which project

through the slotted openings 42 in the casing member 24 (Fig. 5) and also secured by bolts 43 with the brackets 36 (Fig. 8); the heads of the bolts being located in recesses 44 in the portion 9^b of the base and 70 the bolts projected through forked extensions on the brackets and apertures in the casing member.

The casing member 31 has its inner face 75 formed with a circular finished channel 45 arranged concentric to the axis of rotation of the driving shaft 6, and in this channel is secured by bolts 46 (Fig. 6) the stationary grinding head, which is not shown but which is of any usual construction.

In the double disk construction the usual feed hopper is mounted directly on top of the feed spout 21, while in the single disk construction a spacer 48 is secured to the 80 casing members 24 and 31 by bolts 49, and the feed hopper is secured to the spacer by bolt 50.

By the construction described, it will be seen that a base structure is provided which can be used for either the single disk or 90 double disk type of mill so that if it is desired to convert a single disk into a double disk another base structure can be placed end to end with the base structure of the single disk mill; also, that in such conversion the casing parts 22, 24 and 32 of the single disk mill may be discarded and new casing parts 16, 19 and 21 be installed. Further, that reversing this operation, a 95 double disk mill may be readily converted into a single disk. It will also be noted that in view of the fact that the base structures will be exact duplicates, as to construction and finish, the axial alignment of the shafts and the proper fitting of the casing parts 100 will be insured, and, further, that any base unit may be used for either half of the double disk construction, as well as for the single disk construction, thus obviating the necessity of carrying in stock more than the 105 one kind of base unit described.

Having thus described my invention, I claim:—

1. A unitary base member for attrition mills comprising an elongated flat bottom 110 base portion, having an integrally formed bearing support projecting vertically therefrom, a wall likewise formed therefrom extending inwardly from each side of said support, and bearing surfaces formed at 115 the side edge of said wall for the purpose specified.

2. In a grinding mill, a plurality of base members constructed in similarly formed units, each of said units having similarly placed bearing housings for supporting a drive shaft and corresponding points of attachment for removable casing parts whereby any one unit may form the sole base for a certain type of mill or be assembled with 120

another unit to form the base structure of another type of mill.

3. In a machine of the character described, the combination of a plurality of supporting base members, one being a duplicate of the other whereby they become interchangeable one for the other, abutting members formed on said bases having contacting faces, bearing supports also formed on said bases, and means for securing said abutting members together.

4. In a machine of the character described, the combination of a plurality of supporting base members to support a right hand and a left hand machine unit, abutting members at each side of said base members having vertically aligned faces, the base members and abutting members being so arranged that the base members can be interchanged, whereby either one can be used as right hand or left hand members in assembling the machine, and means for securing the abutting ends of the respective base members together.

5. In a grinding mill, a base member formed as a unit capable of use as a single base structure or of being assembled end

to end with another similar unit, said base structure being formed adjacent one end thereof with a supporting wall, said wall 30 when said unit forms the sole base structure constituting a point of attachment and support for grinding casing and feed spout members, said wall being further adapted, when a pair of base units are assembled, to 35 co-operate with the wall of the adjacent unit to form the common support for a plurality of grinding casing and feed spout members.

6. In a grinding mill, a base member arranged to support a longitudinal extending drive shaft, said base member having an abutment at one end whereby a pair of such members may be assembled end to end, together with means for connecting them 45 together, with the ends of the shafts in axial alignment, said assembled base members being each formed adjacent the abutting ends thereof with points of support for 50 casing and feed spout members.

In testimony whereof, I have hereunto set my hand this 16th day of December, 1921.

LOUIS E. BAUER.
